UNITED STATES PATENT OFFICE.

AUGUST P. BJORREGAARD, OF OKMULGEE, OKLAHOMA, ASSIGNOR TO DOHERTY RESEARCH COMPANY, OF NEW YORK, N. Y., A CORPORATION OF DELAWARE.

PROCESS OF UTILIZING PETROLEUM HYDROCARBONS.

Application filed May 3, 1924. Serial No. 710,738.

This invention relates to the art of cracking petroleum and has as its principal object the provision of a process whereby petroleum hydrocarbons may be readily cracked with 5 the production of a high yield of salable products.

Further objects and advantages of the present invention will appear from the following description thereof taken in connection with 10 the accompanying drawing in which

The figure is an elevation diagrammatically illustrating an apparatus in which the petroleum cracking process embodying the preferred form of the invention may be carried 15 out.

It has been known to vaporize petroleum hydrocarbons and to crack vapors so produced by superheating them at substantially atmospheric pressure. This process has a number 20 of seeming advantages over the process of cracking petroleum under super-atmospheric pressure as now commonly practised. However, the atmospheric pressure cracking process has not come into favor owing in a great 25 measure to its low yield of salable products. It has always been found that the percentage of fixed gas has been relatively high and that the yield of light hydrocarbons suitable for gasoline has been relatively low.

According to the present invention the percentage yield of gasoline material is not as high as that from several of the well known pressure cracking processes, but some of the gasoline obtained is of particularly high 30 grade, in that, among other favorable characteristics, some of the gasoline from the present process possesses marked "anti-knock" properties; or, in other words, it does not cause knocking of the engine on ordinary 35 overloads and it may be used satisfactorily in engines having much higher compression ratios than the 4 to 1 or the 4, 5 to 1 ratios now almost universally used in this country. This 40 anti-knock characteristic is much sought after 45 at present, even to the extent of manufacturing special chemicals to mix with the gasoline. Furthermore, the process is so carried on that a high percentage of valuable chemical products and gas is obtained simultaneously and 50 in conjunction with gasoline.

In the apparatus illustrated in the drawing raw material is introduced into the system through pipe 10, which leads to the suction side of pump 12 by which the oil is forced

through pipe 14 into a pipe still 16 or like 55 heating means and in which the oil is partially vaporized and vapors pass through pipe 18 to the upper portion of a separator 20 within which vapors and liquids separate, the liquids passing down into the lower portion 60 of the separator 20, said lower portion being formed to act as a separator 20^a within which heavy ends or residues may segregate from the lighter hydrocarbon liquids. Vapors pass out of the upper portion of chamber 20 65 through pipe 22 to a superheating coil 24 within which the vapors are heated to cracking temperature and pass thence through pipe 26 to the lower portion of a dephlegmator 28. Dephlegmator 28 acts in the usual manner to 70 throw back hydrocarbons having undesirably high boiling points for treatment in subsequent steps of the process and is preferably provided with a cooling coil 30 in its upper portion to increase the space efficiency of the 75 dephlegmator. Liquids condensed out of the vapors by dephlegmator 28 pass downwardly through pipe 32 to the upper portion of liquid separator 20^a where they mingle with the lighter portion of the liquids coming from 80 separating chamber 20 and the mixture of liquids thus formed passes out of the liquid separator 20^a through pipe 34 which connects to pipe 10 on the inlet side of the pump 12 so that the non-vaporized material which is suitable 85 for this purpose is passed back to the heating coil 16. Heavy ends or residues which it is desired to discharge from the system pass out from the lower end of liquid separator 20^a 90 through valved pipe 36.

Vapors from dephlegmator 28 pass out of the top of the dephlegmator through pipe 38 to condenser 40 in which a considerable percentage of the vapors is condensed to form a benzine passing out of the bottom of the 95 condenser 40 through pipe 42 to storage or to a rerun still as desired. Vapors not condensed in condenser 40 leave the lower portion of this condenser through pipe 44.

Prior to this point the process has been carried on substantially at atmospheric pressure. The vapors pass through pipe 44 to a compressor 46. The compressed gases from compressor 46 pass through pipe 48 to the upper part of a cooler 50. A certain amount of condensate forms in cooler 50 and is drawn off from the bottom of the cooler through pipe 52. The condensate drawn off through

pipe 52 may, if desired, be treated with cooled sulfuric acid or other suitable esterifying agent to recover olefines contained therein in the form of esters. This condensate may be 5 added to the benzine from the condenser 40 to be redistilled to recover gasoline. The majority of the vapors entering cooler 50 pass through pipe 54 leaving the cooler 50 near its lower end and discharging into the 10 lower end of absorber 56. The absorber 56 is preferably cooled by refrigerated brine or equivalent means and concentrated sulfuric acid is introduced into the upper end of this absorber through a trap 58, the acid passing 15 down through absorber 56 countercurrent to the hydrocarbons entering the absorber through pipe 54. The temperature at which the absorber 56 is operated is important in that by the temperature control the condensation of gasoline may be controlled and the esterification of the unsaturated hydrocarbons in the vapors and gasoline may be controlled. When using concentrated sulfuric acid as the absorbing agent it is preferred 20 to maintain temperatures at the bottom of the absorber where the vapors enter at about 20° C. to -10° C., depending upon the character of the vapors or the raw stock from which the vapors are produced. Also, the temperatures 25 at the top of the absorber should not rise above 40° C. and are preferably of 30° to 10° C. In the absorber 56, the gases from pipe 54, consisting largely of olefines of a carbon content ranging from C₂ to C₅ are 30 brought into intimate contact with the sulfuric acid. The olefines and acids react in the absorber 56 forming a mixture of dialkyl and acid alkyl sulfates with some sulfuric acid and polymerized olefines, all of which 35 pass out from the bottom of absorber 56 through valved pipe 60. A substantial amount of gasoline is condensed from the gases in the absorber 56 due to low temperature cooling of the brine and the compression 40 of the gases. This gasoline floats to the top of the acid liquor in the absorber and is drawn off through the trapped pipe 62 near the top of the absorber. Unabsorbed gas passes out of the top of the absorber 56 45 through pipe 64 and may be burnt or otherwise disposed of. The alkyl sulfates recovered are preferably diluted with water and dilute sulfuric acid to hydrolyze the sulfates, this hydrolyzing action preferably being carried 50 on immediately after the acid alkyl sulfates are removed from the absorber 56. A portion of the hydrolysis takes place when the water and acid are added to the alkyl sulfates, but the complete hydrolysis is carried 55 on by distilling the acid liquor. Before the distillation is started any benzine or gasoline or unsaturated hydrocarbon liquids and polymerized unsaturated hydrocarbon liquids are removed from the hydrolysis by 60 means of gravity separation because the sat-

urated and unsaturated hydrocarbon compounds are lighter than the acid liquor and rise to the surface. When the hydrolyzed alkyl sulfates have been distilled alcohols corresponding to the various alkyl compounds 70 which are absorbed by the acid are recovered in the condenser as a mixture of alcohols. These alcohols may then be separated by distillation and rectification.

The process of cracking hydrocarbons outlined above is essentially a vapor phase cracking which is carried on at atmospheric pressure. The recovery of the gasoline, however, and other chemical products cannot be advantageously carried on at atmospheric pressure and therefore after the main part of the gasoline stock has been recovered from the cracked vapors, the remaining vapors are treated under pressure in order to recover a large proportion of the gasoline and to recover the chemical products occurring in the gas along with the gasoline. If an attempt was made to recover the gasoline by compression and cooling, the product recovery would be very unstable. However, by treating the 75 compressed vapors under cooled conditions with a cold absorbing acid, the gasoline is recovered as stable gasoline having very valuable properties for use in explosive engines. In particular, as above mentioned, this gasoline has marked "anti-knock" properties. This is true to such an extent that blended 80 gasolines containing considerably less than 1/2 of the kind of gasoline now under consideration are salable at the present time as "anti-knock" gasolines. The portion of the gasoline recovered in the acid absorber has been freed of the lighter hydrocarbons by the 85 esterification with acid and only the stable hydrocarbons remain in the gasoline. On the other hand, the unsaturated hydrocarbons such as ethylene, propylene, butylene, amylene and hexylene, which are absorbed from the gaseous and liquid unsaturated hydrocarbons passing through the absorber, are 90 products from which valuable chemical compounds may be made. Furthermore, the presence of liquid hydrocarbons in the absorber in the presence of acid assists in the 95 absorption of the lighter unsaturated hydrocarbons in the vapors and liquids, so a high 100 percentage of conversion may be effected 105 without the polymerization of olefines.

The process of cracking oil outlined above is particularly adapted for a refinery in that 110 substantially any type of oil may be used as the raw cracking stock. Most pressure cracking processes are limited to the use of gas oil, but in view of the fact that all cracking in the present process takes place in the 115 vapor phase, substantially any form of petroleum distillery slop, heavy or light oils may be used as raw material from which the gasoline and chemical products may be made.

The gas recovered in the process has a com- 120

paratively high heat value, and therefore is well adapted for industrial heating purposes. The alkyl sulfates are preferably treated in known manner as above described in detail to obtain alcohol therefrom and the gasoline from absorber 56 is run to storage. This gasoline is of high degree on the Beaumé scale and needs little treatment to fit it for consumption.

10 Having thus described my invention, I claim:

1. A process of treating petroleum hydrocarbons comprising vaporizing said hydrocarbons, cracking said vapors at substantially 15 atmospheric pressure, condensing out benzine from said vapors, and esterfying olefines formed in the gases by said cracking.

2. A process of treating petroleum hydrocarbons comprising vaporizing said hydrocarbons, cracking said vapors at substantially 20 atmospheric pressure, condensing out benzine from said cracked vapors, contacting the remaining vapors with mineral acid to form alkyl esters, and separating said esters from 25 uncombined hydrocarbon material.

3. A process of treating petroleum hydrocarbons comprising vaporizing said hydrocarbons, cracking said vapors at substantially atmospheric pressure, condensing out benzine 30 from said cracked vapors, contacting the remaining vapors with acid to form alkyl esters and gasoline, and separating said esters from said gasoline.

4. A process of treating petroleum hydrocarbons comprising vaporizing said hydrocarbons, cracking said vapors at substantially atmospheric pressure, condensing out benzine from said cracked vapors, compressing the remaining vapors and cooling them to separate 40 out a second condensate, contacting the compressed vapors with acid to form alkyl esters, and separating said esters from uncombined hydrocarbon material.

5. A process of treating petroleum hydrocarbons comprising vaporizing said hydrocarbons, cracking said vapors at substantially atmospheric pressure, condensing out benzine from said cracked vapors, compressing and cooling the remaining vapors to separate out 50 a second condensate, contacting said compressed vapors with cooled acid to form gasoline and alkyl esters, and separating said esters from said gasoline.

6. A process of treating petroleum hydrocarbons comprising heating said hydrocarbons to vaporize a portion thereof, separating the vapors from the liquid hydrocarbons, heating said vapors to a cracking temperature at substantially atmospheric pressure, dephlegmating said vapors, condensing out benzine from said vapors, compressing the remaining vapors, contacting the compressed vapors with acid to form alkyl esters, and separating said esters from uncombined material.

7. A process of treating petroleum hydrocarbons comprising heating said hydrocarbons to vaporize a portion thereof, separating the vapors from the unvaporized liquid, heating said vapors to cracking temperature at 70 substantially atmospheric pressure, dephlegmating said vapors, condensing out benzine from said vapors, compressing the remaining vapors, contacting said compressed vapors with acid to form alkyl esters and gasoline, 75 and separating said esters from said gasoline.

8. A process of treating petroleum hydrocarbons comprising vaporizing the hydrocarbons, superheating the hydrocarbon vapors while under atmospheric pressure to a cracking 80 temperature, condensing benzine from the cracked vapors, compressing and cooling the remaining vapors to liquefy hydrocarbon material therein, and scrubbing the liquefied and gaseous compressed hydrocarbons with 85 cooled sulfuric acid to esterify unsaturated hydrocarbons therein and separating the esters from uncombined hydrocarbon material.

9. A process of treating petroleum hydrocarbons comprising vaporizing hydrocarbons, 90 superheating the vapors at substantially atmospheric pressure to a cracking temperature, condensing a benzine having a high gasoline content from the cracked vapors, then compressing the remaining vapors and passing the compressed vapors through an absorber counter-current to an acid menstruum 95 passing through the absorber and maintaining the temperature in the absorber below 30°C. 100

10. A process of treating petroleum hydrocarbons comprising heating said hydrocarbons to vaporize a portion thereof, separating the vapors from the liquid hydrocarbons, heating said vapors to a cracking temperature at substantially atmospheric pressure, condensing benzine from the cracked vapors, compressing the remaining vapors and cooling the compressed vapors to liquefy hydrocarbon material therein, and scrubbing the 110 compressed hydrocarbons with cooled sulfuric acid to esterify unsaturated hydrocarbons therein, and separating the esters from uncombined hydrocarbon material. 105

11. A process of treating petroleum hydrocarbons comprising heating said hydrocarbons to vaporize a portion thereof, separating the vapors from the liquid hydrocarbons, heating said vapors to a cracking temperature at substantially atmospheric pressure, 115 dephlegmating said cracked vapors, condensing out benzine from the cracked vapors, compressing the remaining cracked vapors and cooling the compressed vapors to liquefy certain hydrocarbon material therein, removing 120 said liquefied hydrocarbon from the compressed vapors, scrubbing liquefied and gaseous compressed hydrocarbons with cooled sulfuric acid to esterify unsaturated hydrocarbons therein with simultaneous production 125 130

of "anti-knock" gasoline, and separating the esters from uncombined hydrocarbon material.

12. As an article of manufacture a motor gasoline formed by contacting cooled sulfuric acid with petroleum hydrocarbon vapors which have been cracked in the vapor phase and at substantially atmospheric pressure, and having "anti-knock" properties.

10 13. The method of making "anti-knock" gasoline and alkyl esters comprising contacting cooled sulphuric acid with petroleum hydrocarbon vapors which have been cracked in the vapor phase and substantially at atmospheric pressure.

15 14. A liquid motor fuel having "anti-

knock" properties, comprising a gasoline-like liquid produced by contacting petroleum vapors resulting from cracking petroleum oil in vapor phase at substantially atmospheric pressure with cold sulphuric acid maintained under a super-atmospheric pressure. 20

15. The method of making a gasoline motor fuel which comprises cracking hydrocarbon oil in vapor phase, increasing the pressure 25 on the resulting cracked vapors and simultaneously cooling and contacting the cracked vapors with sulfuric acid while maintaining said increased pressure.

In testimony whereof I affix my signature.

AUGUST P. BJERREGAARD.
